COMBINED DUPLICATOR AND THERMO- GRAPHIC MASTER-MAKER

Courtney A. Leubner, Oakbrook, Ill., assignor to Bell & Howell Company, Chicago, Ill., a corporation of Illinois

Filed Sept. 22, 1965, Ser. No. 87,105

Term of patent 14 years

(Cl. D64—11)

Fig. 1.

Fig. 2.

FIGURE 1 is an isometric view of a combined duplicator and thermographic master-maker embodying my new design.

FIGURE 2 is another isometric view thereof showing the sides opposite to those of FIGURE 1.

FIGURE 3 shows the same view as FIGURE 1 except that the broken line illustrations of FIGURE 1 have been removed for clarity of illustration.

FIGURE 4 shows the same view as FIGURE 2 except that the broken line illustrations of FIGURE 2 have been removed for clarity of illustration.

I claim:

The ornamental design for a combined duplicator and thermographic master-maker, as shown and described.
